UNITED STATES PATENT OFFICE.

CHARLES L. GOODRUM, OF BROOKLYN, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

1,221,167.

Specification of Letters Patent.

Patented Apr. 3, 1917.

Application filed September 11, 1916. Serial No. 119,507.

To all whom it may concern:

Be it known that I, CHARLES L. GOODRUM, a citizen of the United States, residing at Brooklyn, in the county of Kings and State of New York, have invented certain new and useful Improvements in Automatic Telephone-Exchange Systems, of which the following is a full, clear, concise, and exact description.

10 This invention relates to automatic telephone exchange systems, and more particularly to circuit arrangements for controlling the operation of a switch which is set in accordance with directive impulses sent out by 15 a calling subscriber.

The object of this invention is to provide simple and efficient means for controlling the operation of a switch in response to impulses.

20 A feature of this invention is a line relay having a secondary winding in inductive relation to its primary winding. Current set up in such secondary winding controls a polarized relay to interrupt the circuit of a 25 stepping magnet.

A further feature of the invention is an arrangement by which the line relay remains energized during the sending of impulses to hold open the circuit of a release magnet.

30 The invention has been shown applied to a selector switch of the well-known step-by-step type, and may obviously be used for controlling switches of various types.

It is thought that the invention will be 35 best understood from the following detailed description, reference being had to the accompanying drawing.

In the drawing the circuits of a selector switch are shown in full and at the left is 40 shown a subscriber's substation apparatus.

When the subscriber at substation 1 desires to initiate a call, he removes his receiver from the hook, whereupon his line is extended by means of a line finder or other 45 suitable device indicated by dotted lines at 2 and 3 to the selector shown in the drawing. Line relay 4 is then energized over a circuit from positive pole of battery, left-hand winding of relay 4, conductor 5, side-switch wiper 6 in its first position, line conductor 2, the substation apparatus of the calling subscriber, contact springs 7 of an impulse sending device 8, line conductor 3, side-switch wiper 9 in its first position, conductor 10 and right-hand winding of relay 4

to negative pole of battery. Relay 4 is energized and remains energized until the side switch moves into position 3, regardless of the operation of the sender 8, this circuit being maintained by a shunting resistance 11, 60 which allows sufficient current to flow when contact springs 7 are separated to hold up relay 4.

When the circuit just traced was completed, an impulse was induced in a secondary winding of relay 4, this winding being in a circuit in series with a polarized relay 11, by means of conductors 12 and 13. This impulse, however, is of such polarity as not to cause the operation of relay 11. 70

The calling subscriber now operates the sender 8 to transmit a desired number of impulses. At the first break of the circuit through contact springs 7, an impulse of a polarity such as to cause the operation of relay 11 is induced through the secondary winding of relay 4. Relay 11 attracts its armature and closes a circuit for the primary stepping magnet 14, from grounded battery, winding of magnet 14 to ground at the 80 armature and front contact of relay 11. When the contact springs 7 again close, an impulse is again induced in the secondary winding of relay 4, but this time of such polarity as not to cause the operation of 85 relay 11. It will thus be seen that by the use of a polarized relay, an impulse will be transmitted to the primary stepping magnet for each make-and-break of the circuit, whereas an ordinary relay, used in place of 90 a polarized relay, would send an impulse on each make and on each break of the line circuit.

When relay 11 first attracted its armature, it completed a circuit for slow release 95 escape magnet 15, from grounded battery, winding of magnet 15, side-switch wiper 16 in its first position, conductor 17, armature and front contact of relay 11 to ground. The escape magnet is energized, and being 100 slow to release, remains energized during the sending of the series of impulses.

After the series of impulses have been sent, the armature of relay 11 remains retracted for a comparatively long time and 105 escape magnet 15 is deenergized, releasing the side-switch wipers controlled by it into their second position.

In the second position of the side switch, a circuit is closed for a secondary stepping 110

magnet 18 from grounded battery, the winding of magnet 18, its armature and back contact, side-switch wiper 19 in its second position, and the armature and back contact 5 of escape magnet 15, to ground. The secondary stepping magnet 18 interrupts its own circuit and causes a brush set including brushes 20, 21 and 22 to travel over the terminal sets of trunks in the desired group, 10 a set of such terminals being indicated at 23, 24 and 25.

Assuming now that an idle condition of trunks is indicated by ground on test terminals 25, and a busy condition by the absence of such ground, the secondary magnet will continue to advance the brush set 15 until test brush 22 encounters a terminal 25 having ground thereon. When this takes place, escape magnet 15 is energized over 20 a circuit from grounded battery, winding of escape magnet 15, side-switch wiper 16 in its second position, brush 22 and terminal 25 to ground. The energization of the escape magnet releases the side-switch wipers into 25 their third position, and permanently opens the circuit of stepping magnet 18. The subscriber's line has now been advanced to a succeeding switch, which may be a connector or another selector.

30 If the subscriber desires to abandon a call while the side-switch wipers are in either their first or second positions, the deenergization of line relay 4 will result in energization of a release magnet 26, its circuit 35 being from grounded battery, winding of magnet 26, off-normal contact 27, side-switch wiper 28 in either first or second position, and armature and back contact of relay 4 to ground. This release magnet 26, 40 on energization completes a locking circuit for itself through its armature and front contact, which maintains it energized until the switch is fully restored, at which time this locking circuit is broken by the operation of off-normal contact 27.

After the side switch has moved its wipers into their third position, the release of the switch is controlled by the succeeding switch. The restoration of the preceding 50 switch will put a ground on terminal 25. A circuit is then completed for release magnet 26 from grounded battery, winding of magnet 26, off-normal contact 27, side-switch wiper 28 in its third position, brush 22 and

terminal 25 to ground. The release magnet 55 locks up and controls the release of the switch as previously described.

What is claimed is:

1. In a control circuit, a relay having a primary winding and a secondary winding 60 in inductive relation thereto, a polarized stepping relay in circuit with said secondary winding, a stepping magnet controlled by said stepping relay, a release magnet, and a circuit therefor extending through a back 65 contact of said first relay.

2. In a telephone exchange system, an automatic switch, an impulse circuit therefor, a polarized relay, a stepping magnet controlled thereby, a circuit for said relay, a relay 70 arranged to inductively unite said circuits, a release magnet, and a circuit therefor, said circuit extending through a front contact of said last named relay.

3. In a telephone exchange system, an incoming line, outgoing lines, an automatic switch for interconnecting said lines, a relay having a primary winding in circuit with said incoming line and a secondary winding 75 in inductive relation thereto, and an impulse sending device for transmitting impulses to said relay, means to control the operation of said switch by currents induced in said secondary winding by such impulses, said relay being maintained energized during the sending of impulses.

4. In a telephone exchange system, an incoming line, outgoing lines, an automatic switch for interconnecting said lines, controlling circuits therefor, a controlling 90 switch including a plurality of wipers and contacts, an impulse sending device, a relay having two windings in inductive relation for controlling the setting of said automatic switch, and means including a back contact 95 of said relay for preventing the release of said automatic switch in certain positions of said controlling switch.

5. An automatic switch, an impulse circuit therefor, a circuit controlling the operation of said switch, and means for inductively uniting said circuits, said means being arranged to prevent the release of said switch in certain stages of its operation.

In witness whereof, I hereunto subscribe 100 my name this 8th day of September A. D., 1916.

CHARLES L. GOODRUM.
